LESLIE O. PARKER, OF ANDERSON, INDIANA, ASSIGNOR TO DELCO-REMY CORPORATION, OF DAYTON, OHIO, A CORPORATION OF DELAWARE

ELECTRIC LAMP

Application filed June 13, 1927. Serial No. 198,406.

This invention relates to a lens for a rear signal lamp adapted to be used in connection with automotive vehicles.

It is among the objects of the present invention to provide a lens which will distinctly transmit a stop signal.

Further objects and advantages of the present invention will be apparent from the following description, reference being had to the accompanying drawings, wherein a preferred form of embodiment of the present invention is clearly shown.

In the drawings:

Fig. 1 illustrates a signal lamp in front elevation in which the lens is used;

Fig. 2 is a sectional view taken along the line 2—2 of Fig. 1;

Fig. 3 is an enlarged fragmentary view showing one of the depressions in the lens forming a letter of the word "Stop";

Fig. 4 is a detail section taken along the line 4—4 of Fig. 3; and

Fig. 5 is a detail sectional view taken along the line 5—5 of Fig. 3.

Referring to the drawing, the signal lamp 20 is shown having a frame 21 in which the lens 22 is supported so that the rear surface 23 of said lens is substantially vertical as shown in Fig. 2.

The front face of the lens is provided with a plurality of concavo-cylindrical flutes 24 arranged vertically for spreading the light sidewise. This front face of the lens is inclined to the rear surface of said lens so as to reflect light in a direction inclined to a plane at right angles to the said rear surface of said lens. The present drawing shows this inclination so that the refraction of the light is upwardly inclined as regards said plane.

The rear face of the lens described by the numeral 25 is provided with a plurality of depressions 26 which form the letters of the word "Stop" or other legend. As shown in the drawing, the depressions are comparative-

ly deeper adjacent the bottom of the lens than they are at the top. The inner surfaces of the depressions are provided with a plurality of raised portions 27, quarter-spherically shaped and arranged in spaced, horizontal rows as shown in the Fig. 3. The spherically

shaped surfaces of the raised portions are adapted to refract the light striking them in an upwardly direction. The flat sides of said raised portions are on the upper side, or more specifically that side toward the top of the lens. The rear surface of the lens not depressed is opaqued so that passage of light through this portion is substantially prevented.

Light passing from the lamp 30 provided in the signal device 20 is reflected by the reflector 31, the rays striking the raised portions in the depressions of the lens and being deflected upwardly. The inclined fluted front face of the lens also tends to direct these rays in an upwardly direction so that the stop signal is clearly discernible within an area substantially at the level of the eyes of the operator driving the car behind. The raised portions with their spherical surfaces tend to provide small globule light areas of comparatively good light reflecting qualities which tend to transmit the light within the depressed portion of the lens, thereby causing the word "Stop" formed by said depression to stand out distinctly.

I claim as my invention:

1. A lens for a signal lamp comprising, depressions in the rear face thereof which form the letters of a legend, the inner surfaces of said depressions having quarter-spherically shaped raised areas arranged in spaced, horizontal rows and having their bases toward the top of the lens to direct light upwardly by refraction.

2. A lens for a signal lamp comprising, depressions in the rear face thereof which form the letters of a legend, said depressions varying in depth so that the inner surfaces thereof are inclined to the rear surface of the lens, said inner surfaces being provided with quarter-spherically shaped raised areas arranged in spaced, horizontal rows.

3. A lens for a signal lamp comprising, depressions in the rear face of the lens which form the letters of a legend, the inner surfaces of said depressions having quarter-spherically shaped raised areas, spaced and arranged in spaced horizontal rows, the flat sides of the

said raised areas being toward the top of the lens.

4. A lens for a signal lamp comprising, a front face provided with concavo-cylindrical flutes, arranged vertically and inclined to the rear surface of the lens, the rear face of said lens having depressions which form the letters of a legend, the inner surface of said depressions having quarter-spherically shaped 10 raised areas, spaced, and arranged in spaced horizontal rows, the portion of the rear face of the lens not depressed being provided with an opaque surface substantially to prevent light from passing through the lens portion 15 other than those provided with the quarter-spherically shaped raised portion.

5. A lens for a signal lamp comprising, depressions in the rear face thereof which form the letters of a legend, spaced raised portions arranged in spaced horizontal rows, said raised portions being in the form of segments of prisms having their bases disposed toward the top of the lens to direct light upwardly by refraction.

25 6. A lens for a signal lamp formed to provide letters and a contrasting background, the letter area being formed to provide a series of segments of prisms having their bases disposed toward the top of the lens to throw 30 light upwardly.

7. A lens for a signal lamp formed to provide letters and a contrasting background, the letter area being formed to provide a series of segments of prisms having their bases disposed toward the top of the lens to throw light upwardly, said segments likewise tapering toward a side of the lens to produce lateral spread of light.

40 8. A lens for a signal lamp comprising depressions in the rear face thereof which form the letters of a legend, the bottoms of said depressions being formed to provide a series of segments of prisms having their bases disposed toward the top of the lens to throw 45 light upwardly.

9. A lens for a signal lamp comprising depressions in the rear face which form the letters of a legend, said depressions being set in a contrasting background, the bottoms of said 50 depressions being formed to provide a series of segments of prisms having their bases disposed toward the top of the lens to throw light upwardly.

In testimony whereof I hereto affix my
55 signature.

LESLIE O. PARKER.
